UNITED STATES PATENT OFFICE.

NORWOOD H. KNOWLTON, OF ROCKPORT, MASSACHUSETTS, ASSIGNOR TO UNITED SHOE MACHINERY CORPORATION, OF PATERSON, NEW JERSEY, A CORPORATION OF NEW JERSEY.

HEEL-TRIMMING MACHINE.

Application filed June 8, 1927. Serial No. 197,392.

This invention relates to heel-trimming machines and is herein illustrated as embodied in a machine for trimming the toplift of a heel flush with a heel body that 5 has previously had the final shape imparted to it. It is to be understood, however, that in certain aspects the invention is not limited to the particular operation hereinafter described nor to the particular details of construction illustrated.

In the manufacture of wood heels, it is common practice to apply a cover of thin sheet material to the body of a heel and thereafter attach an over-size toplift. It 15 then becomes necessary to trim the perimeter of the toplift flush, or approximately flush, with the body of the covered heel. In most cases this trimming operation is performed before the heel is attached to a 20 shoe, by holding the heel with one hand while the cutter of a trimming machine operates on the toplift, since the shape and proportions of an unattached heel are such that it is not convenient or feasible to grasp 25 the heel with both hands. Consequently, the power with which an operative may hold and manipulate a heel while the toplift is being trimmed is limited to the strength of 30 the fingers as contrasted to the more powerful hold with which an operative may grasp a shoe with both hands, as when trimming 35 an entire heel that is affixed to a shoe. Moreover, manufacturing conditions require much more rapid work when only the toplift is to be trimmed than when the entire heel is to be trimmed.

In a machine for trimming toplifts it is necessary to maintain the tread surface of the toplift in a certain plane while the 40 heel is being turned to cause progress of the trimming cut around the sides and back of the toplift, and for this purpose it is common practice to provide a tread rest against which the toplift is held. It is also common practice to use the same tread rest to 45 position the heel relatively to the trimming cutter while the breast of the toplift is being trimmed, although usually the profile of the heel is such that it is desirable, and in some 50 cases actually necessary, to give the tread rest a different angular position when trimming the breast. To insure a firm bearing of the toplift against the tread rest requires some pressure, and when the work-engaging

element of the tread rest is stationary, as 55 heretofore, its frictional resistance to manipulation of the heel materially retards production and quickly fatigues the operative.

In view of the conditions above described, an object of the invention is to provide an 60 improved tread-rest that will not offer appreciable resistance to rotary or other movement of a heel or toplift held against it. Accordingly, the invention provides an improved tread-rest the work-engaging element 65 of which comprises a plurality of anti-friction rollers, for example hardened steel balls. Balls are preferred since they may rotate in any direction and are therefore best suited to the conditions encountered in 70 trimming a heel or toplift.

In the illustrated construction the anti-friction balls are arranged in and protrude from individual sockets formed entirely in 75 one plate, and are sustained against the pressure of the work and maintained in their sockets by a solid retaining plate of hardened steel having a flat ball-engaging surface. The flat retaining means thus engages each ball at but a single point which 80 is diametrically opposite the work-engaging point of the ball. This construction does not require special accuracy in registering the plates, and does not offer appreciable resistance to rotation of the balls. 85

When a device of the character above described is used in the vicinity of a trimming cutter, it is inevitable that some dust, dirt, and chips produced by the cutter will become lodged in the ball sockets and, if retained 90 therein and accumulated, would appreciably resist rotation of the balls or altogether prevent rotation and thus impair or destroy the effectiveness of the anti-frictional construction. 95

Accordingly, another object of the invention is to provide a ball-bearing tread-rest from the sockets of which dust and dirt will be automatically discharged. To this end a novel feature of the invention consists 100 in an organization in which the socket plate and the retaining plate are spaced from each other to provide a chamber into which the dust and dirt may escape from the rear ends of the ball-sockets, and in which, as illustrated, these plates are arranged in a substantially upright position so that the dust and dirt may escape from said chamber by 105

dropping through an opening at the bottom thereof.

When leather toplifts are used it is the practice to attach them so that the flesh side of the leather will be at the attaching face while the grain side is at the tread face. Consequently, the trimming of a toplift involves the problem of obtaining a clean cut at the attaching surface, where the fleshy and more or less spongy character of the leather militates against cutting and tends to produce fuzz which detracts from the appearance of the completed work. By reason of this difficulty in obtaining a clean cut at the flesh side of the toplift, former machines for doing this work have been provided with rotary cutters arranged to chop the toplift from the flesh side toward the grain side. In such machines the direction of travel of the cutting edges is transverse to the plane of the toplift, and the result is not entirely satisfactory since the individual chopping cuts do not always merge one with another as they should to make the contour of the toplift smooth and even.

In view of the latter difficulty, the illustrated machine is provided with a rotary toothed cutter the cutting edges of which will cut in the direction of the contour of the toplift and at the same time produce flush trimming and execute a clean cut at the flesh side instead of leaving fuzz projecting therefrom. To this end the illustrated cutter is provided with helical cutting edges formed and arranged to trim a toplift flush with the body of a heel and with inclined draw cuts that tend to force the stock at the attaching face of the toplift toward the tread face thereof, thereby utilizing the denser and firmer stock at the tread side of the toplift as a cutting bed against which to cut the relatively spongy stock of the toplift flush with the body of the heel. The novel features by which this improved result is obtained forms the subject-matter of my divisional application Serial No. 297,499 filed August 4, 1928.

Referring to the drawings,

Fig. 1 is a left side elevation of a portion of a heel-trimming machine embodying the present invention;

Fig. 2 is a front elevation thereof;

Fig. 3 is a vertical section on a larger scale, through the trimming cutter and the tread rest, and shows a heel the toplift of which is in process of being trimmed;

Fig. 4 is a perspective view of a trimming cutter embodying the improved construction hereinbefore referred to; and

Fig. 5 is a vertical section, on a larger scale, of a fragment of the ball-bearing tread-rest.

The frame of the illustrated machine includes a head 10 and a supporting column 12. Suitable bearings, one of which is in-

dicated at 14, are formed in the head 10 for a horizontal cutter shaft 16. This shaft is provided with a pulley 18 to be driven by a belt.

The improved trimming cutter 20, which is shown best by Fig. 4, is formed with a series of cutting teeth each having a helical cutting edge 22. Notches 24 are formed in the teeth to produce a bead on the toplift adjacent to the tread surface, but these notches may be omitted if no bead is desired. Any preferred means may be used to attach the cutter 20 to the shaft 16, the means shown in Fig. 3 being well known and commonly used to attach forepart trimming cutters to similar shafts. For this purpose the shaft 16 is provided with a conical portion 26 which supports an internally tapered split thimble or bushing 28. A flange 30 projecting radially from the rear end of the bushing 28 forms an abutment for the hub 32 of the cutter 20 so that when the cutter is forced toward the larger end of the conical portion 26 by the attaching screw 34 and washer 36 it will carry the bushing 28 with it and thereby produce expansion of the bushing and a consequent gripping of the cutter by the bushing.

A tread-rest 40 is arranged under the cutter 20 so that the lower edge of the latter may be used to do the trimming. This tread-rest, as shown, comprises a base 42, two upright plates 44 and 46 of hardened steel, and a plurality of rollers, for example, steel balls 58. Cylindric sockets 56 extend through the entire thickness of the plate 46 to house the balls individually. A small portion of each ball protrudes from the front end of its socket to provide an antifriction bearing for the tread surface of a heel or toplift. Retaining flanges 57 (Fig. 5) are formed at the front ends of the sockets. The thickness of the plate 46 is substantially less than the diameter of the balls, but the sockets have greater diameter than the balls to enable the latter to rotate easily and to permit dust to pass readily through the sockets.

The balls are maintained in their sockets by the back plate 44 which has a flat imperforate ball-engaging surface to sustain the pressure of the work against the balls and to insure the desired protrusion of the balls from the front plate 46. Thus, each ball has contact with the back plate at only a single point which is diametrically opposite its work-engaging point. Moreover, each ball is engaged by its socket at a point midway between its front and rear faces. This construction avoids wedging of the balls and enables them to rotate in any direction with the least frictional resistance.

The socket plate and the back plate are spaced apart to provide a dust chamber 52 between them. The spaced relation is obtained by flanges 48 and 50, 50 formed on

the rear face of the socket plate and seated against the front face of the retaining plate. Screws 54 (Fig. 2) fasten both of these plates to the base 42. The flange 48 preferably extends all the way across the upper margins of the plates to prevent dust and chips from entering the top of the chamber 52. It is inevitable, however, that some dust from trimming will enter the sockets 56 through the front face of the plate 46, but such dust will be dislodged by rotation of the balls and ejected into the chamber 52 instead of accumulating in the sockets and becoming closely packed. To provide for the escape of any dust or dirt that finds entrance into the chamber 52 through the sockets 56 the chamber is open at the bottom. Furthermore, the gaps 60, 60 between the spacing flange 48 and the upper ends of the spacing flanges 50 provide for the escape of dust into a pneumatic suction trunk with which trimming machines of this general character are sometimes provided. Of course, when a pneumatic suction trunk is connected to one or both of the gaps 60 it exhausts the dust from the chamber 52 and from each of the sockets 56.

The profiles of heels of various types differ one from another in pitch or inclination as well as in other respects, and to provide for angular adjustment of the tread rest in accordance with various pitches or other requirements, the tread rest is supported by horizontal trunnions 62. These trunnions 35 are affixed to supporting arms 64 formed on a bracket 66. An arm 68 projects from one side of the tread rest toward the rear and is provided with a segmental slot 70 through which a clamping bolt 72 projects from the 40 brackets 66. A wing nut 74 carried by the bolt 72 is arranged to clamp the arm 68 against the bracket 66, while the slot 70 provides for angular adjustment of the tread rest about the axis of the trunnions 62.

45 The illustrated construction also provides for vertical adjustment of the tread rest. This adjustment is obtained by adjusting the bracket 66 up or down relatively to the member 76 by which it is supported. Clamping bolts 78 extend through vertically extending slots formed in the bracket 66 and have screw-thread engagement with the supporting member 76. An adjusting screw 80 abuts a lower surface of the bracket 66 to effect the 50 desired vertical adjustment and the bolts 78 serve to fasten the bracket at various positions of adjustment.

55 Provision is also made for adjusting the tread rest from front to rear, that is, in lines parallel to the axis of the cutter shaft 16. For this purpose the supporting member 76 is provided with a horizontal cylindric shank 82 which extends through a bore in the head 10 and is provided with a screw 60 thread at its rear end and with an adjusting

nut 84. The bottom of the member 76 is mortised into a split clamping fixture 83 which is tightened by a screw 85 to hold the member 76 rigidly.

A vertically adjustable heel guard 86 is 70 arranged in front of the trimming cutter 20 to engage the body 88 of a heel adjacent to the toplift 90, as shown in Fig. 3. In practice this guard will be adjusted to locate its lower edge at or near the level of the 75 bottom of the trimming cutter. The guard 86 is secured to a stationary bracket 92 by a clamping bolt 94 and plate 96. The guard 86 is formed with a vertical slot 98 to provide for vertical adjustment, and the member 92 is provided with a screw 100 to effect such adjustment. This screw is formed with a flange 102 that enters a notch formed in the rear face of the guard 86.

The direction of rotation of the cutter 20 85 is indicated by arrows in Figs. 1, 2 and 4, and, since the axis of rotation is heightwise of the heel being trimmed, it will be apparent that these edges will progress, while in contact with the toplift, in the direction 90 of the contour of the toplift. Moreover, the inclination of the cutting edges is such as to tend to force the stock at the attaching face of the toplift toward the tread face, and since the flesh side of the toplift is always at 95 the attaching face, the fleshy substance will be forced toward the leather of greater density which is at the tread face. Consequently, the fleshy substance as well as the firmer substance of the toplift will be 100 trimmed with a clean cut progressing lengthwise of the contour of the toplift. The anti-friction balls 58, being free to rotate in any direction, greatly facilitate the manipulation of the work while the toplift is seated 105 against them, whether the heel is turned incidental to trimming around the sides and back of the toplift or moved bodily from side to side incidental to trimming the breast.

110 Having thus described my invention, what I claim as new and desire to secure by Letters Patent of the United States is:

1. In a heel-trimming machine, a tread-rest comprising a plate having a plurality 115 of sockets extending therethrough, anti-friction members arranged in said sockets so that portions thereof protrude therefrom to provide bearings for the tread face of a heel, and means having a flat surface arranged to engage said anti-friction members at points diametrically opposite the work-engaging points of the members to retain them in said sockets, said means being spaced from said plate to enable dust to escape from the rear 120 ends of said sockets.

2. In a heel-trimming machine, a tread-rest comprising a plate having a plurality 125 of sockets extending therethrough, rotatable steel balls arranged in said sockets so that 130

portions thereof protrude therefrom to provide bearings for the tread surface of a heel, and a plate having a flat surface arranged to engage said balls at points diametrically opposite the work-engaging points of the balls to sustain the pressure of the work against the balls, said plates being spaced to enable dust to escape from the rear ends of said sockets.

- 10 3. In a heel-trimming machine, a tread-rest comprising a front plate having a plurality of sockets extending through its entire thickness, anti-friction balls rotatably arranged in said sockets so that portions thereof protrude from said sockets to provide bearings for the tread face of a heel, and a back plate having a flat imperforate surface arranged to engage said balls at points diametrically opposite the work-engaging points of the balls to maintain the latter in operative positions, said plates being spaced apart from each other to provide a chamber into which dust may escape from said sockets.
- 15 4. In a heel-trimming machine having a trimming cutter, a tread rest arranged adjacent to said cutter, said tread-rest comprising a front plate and a back plate arranged

in substantially upright position in confronting relation but spaced apart to provide a dust-chamber, said front plate having a plurality of sockets extending through its entire thickness, anti-friction rollers arranged in said sockets and maintained therein by said back plate so that portions thereof protrude from the sockets to provide a bearing for the tread face of a heel, and means arranged to close the top of said dust chamber.

5. In a heel-trimming machine, a tread-rest comprising a plate having a plurality of cylindric sockets and internal flanges at the front ends of said sockets, anti-friction balls arranged to rotate in said sockets and protrude beyond said flanges to provide a bearing for the tread face of a heel or top-lift, and means arranged to engage said balls at points diametrically opposite their work-engaging points to maintain them in their operative positions, said means being spaced from said plate to enable dust to escape from the rear ends of said sockets.

In testimony whereof I have signed my name to this specification.

NORWOOD H. KNOWLTON.
